UNITED STATES PATENT OFFICE.

SAMUEL THORNLEY, HARRY THORNLEY, AND JAMES BOOTH, OF HYDE, ENGLAND.

BANDEAU FOR HATS.

1,089,291.

Specification of Letters Patent.

Patented Mar. 3, 1914.

Application filed June 6, 1912. Serial No. 702,029.

To all whom it may concern:

Be it known that we, SAMUEL THORNLEY, HARRY THORNLEY, and JAMES BOOTH, British subjects, residing at Hyde, county of 5 Chester, England, have invented certain new and useful Improvements in Bandeaux for Hats, of which the following is a specification.

This invention relates to bandeaux for 10 ladies' hats and refers particularly to improvements in the manufacture and construction thereof.

It is customary to block or shape bandeaux to conical form to fit into the interior 15 of the hat and also to make them of various sizes to fit different sizes of hats which necessitates a large stock to insure accurate fitting and further it has been proposed to make frusto-conically blocked bandeaux 20 from a strip with overlapping edges, having hooks or press buttons or similar means of fastening, for the purpose of adjusting them to the hat.

This invention consists essentially in 25 forming or stamping an annular bandeau from perfectly flat material without any shaping or blocking and with overlapping ends so that by drawing the ends over one another a frusto-conical shape is produced 30 and the bandeau may be enlarged or reduced in size as desired.

The invention will be fully described with reference to the accompanying drawings.

Figure 1. is a plan view of the finished 35 bandeau. Fig. 2. is a transverse section. Figs. 3 and 4 are side elevations showing the frusto-conical form the bandeau will assume when the ends are drawn over one another. Fig. 5. is a plan view of a blank 40 of stamped buckram or other stiff material from which the bandeau is made. Fig. 6. is a plan from the underside showing the method of construction of the bandeau. Fig. 7. is a section through the overlapping 45 ends showing a spring button attachment. Fig. 8 is a plan view of the overlapping ends showing another attachment for the ends.

Fig. 9. is a side elevation of bandeau with ends drawn over and held by a metal loop. Fig. 10 is a perspective view of a clip which 50 may be used for attaching the overlapping ends.

In constructing the bandeau we stamp from a flat sheet of buckram or other suitable stiff material an annular piece or ring 55 A with severed ends a. The annular ring A of stiff material is covered on the front side (or on both sides) with a piece B of velveteen, velveteen or other fabric preferably cut on the bias. The fabric B is turned 60 over both the outer and inner edges b b' of the stiff annular piece A and stitched either with or without a piping C of cane, cord or similar material. Two elastic loops D one stitched and the other loose, are applied 65 to one end (see Figs. 1 and 3) to retain the overlapping ends a in position. Or instead of elastic loops, metal clips d (Fig. 4), 70 spring buttons (Fig. 7), buttons and button holes (Fig. 8), metal loops e (Fig. 9), 75 or other forms of catches may be employed to retain the overlapping ends in position. Or all such fastenings may be dispensed with and the ends be formed or stitched to hold them in the desired position. 75

The advantage of this construction is that no blocking or shaping is required, but the frusto-conical shape, where required, is obtained by overlapping the ends of the flat annular bandeau, and further the bandeau 80 is readily adjustable to any size of hat.

What we claim as our invention and desire to protect by Letters Patent is:—

1. As a new article of manufacture, a bandeau for hats comprising a flat, annular 85 strip of stiff material with severed ends adapted to be overlapped and drawn past each other to convert said annular strip into frusto-conical shape; a covering of fabric attached to said annular strip; and means for holding said ends together when in overlapped position.

2. As a new article of manufacture, a bandeau for hats comprising a flat, annular

strip of buckram with severed ends adapted to be overlapped and drawn past each other to convert said annular strip into frusto-conical shape; a covering of fabric attached to said annular strip; and elastic loops carried by said annular strip for holding said ends together when the same are in overlapped position.

In testimony whereof we have hereunto

set our hands in presence of two subscr- 10
ing witnesses.

SAMUEL THORNLEY.
HARRY THORNLEY.
JAMES BOOTH.
